US00D807495S

(12) **United States Design Patent** (10) Patent No.: **US D807,495 S**
Hirsch et al. (45) Date of Patent: ** Jan. 9, 2018

(54) **RECESSED CHILLED BEAM**

(71) Applicant: **Air Distribution Technologies IP, LLC.**, Milwaukee, WI (US)

(72) Inventors: **Joachim Hirsch**, Colleyville, TX (US); **Honghui Zhang**, Richardson, TX (US); **Ernest Freeman**, Dallas, TX (US); **Keith Glasch**, Plano, TX (US); **Blake Robert Gallagher**, Seattle, WA (US); **Paul Sheppard Woolford**, San Francisco, CA (US); **Thomas Adam Kaczkowski**, University City, MO (US)

(73) Assignee: **Air System Components, Inc.**, Plano, TX (US)

(**) Term: **14 Years**

(21) Appl. No.: **29/524,249**

(22) Filed: **Apr. 17, 2015**

(51) LOC (11) Cl. **23-04**

(52) U.S. Cl.

USPC **D23/393**

(57) **CLAIM**

The ornamental design for a recessed chilled beam, as shown and described.

DESCRIPTION

FIG. 1 is a perspective view of a recessed chilled beam; FIG. 2 is a side view thereof; FIG. 3 is a side view thereof; FIG. 4 is an end view thereof; FIG. 5 is an end view thereof; FIG. 6 is an overhead view thereof; FIG. 7 is a bottom view thereof; and, FIG. 8 is perspective view thereof shown in a position of use within environment.

(Continued)

The broken lines present in all FIG. views represent portions of the article and environment of the design in a position of use that form no part of the claimed design.

1 Claim, 7 Drawing Sheets
